Fig. 5.

Fig. 6.

Fig. 7.

Fig. 8.

FIGURE 1 is a front perspective view of a bookcase showing my design wherein each depending front edge portion of the top and bottom shelf members defines a horseshoe curve.

FIGURE 2 is a front elevational view of the embodiment of a bookcase illustrated in FIGURE 1.

FIGURE 3 is a right side elevational view thereof.

FIGURE 4 is a cross sectional view taken along line 3—3 of FIGURE 1.

FIGURE 5 is a rear elevational view of the embodiment illustrated in FIGURE 1,

FIGURE 6 is a top plan view thereof,

FIGURE 7 is a bottom plan view thereof,

FIGURE 8 is a cross sectional view taken along line 7—7 of FIGURE 3,

FIGURE 9 is a front elevational view of a second embodiment of my bookcase wherein each depending front edge portion of the top and bottom shelf members is in the form of an ogee curve.

FIGURE 10 is a right side elevational view of the em-

bodiment illustrated in FIGURE 8. It should be understood that the left side elevational view is a mirror image of FIGURE 9.

The sides not shown in FIGURES 3 and 10 are mirror images of the sides shown.

I claim:

The ornamental design for a bookcase, substantially as shown and described.
